WILLIAM A. DAGGETT, OF SOUTH VINELAND, NEW JERSEY.

Letters Patent No. 89,131, dated April 20, 1869.

IMPROVED CLOTHES-FRAME.

The Schedule referred to in these Letters Patent and making part of the same.

To all whom it may concern:

Be it known that I, WILLIAM A. DAGGETT, of South Vineland, in the county of Cumberland, and State of New Jersey, have invented a new and improved Clothes-Frame; and I do hereby declare that the following is a full, clear, and exact description thereof, which will enable others skilled in the art to make and use the same, reference being had to the accompanying drawings, forming part of this specification, in which—

Figure 1 is a side view of my improved clothes-frame, several of the single bars being extended, and parts being broken away to show the construction.

Figure 2 is a detail view of a portion of the reverse side of the frame, showing the button.

Similar letters of reference indicate corresponding parts.

My invention has for its object to furnish a simple, convenient, strong, and durable clothes-frame, which shall be so constructed and arranged that when extended, it may furnish a large drying-surface, and, when closed, it may shut up into small compass; and

It consists in the construction and combination of various parts of the frame, as hereinafter more fully described.

A are the horizontal bars of the frame, which are arranged in sets, three bars being in each set.

To the outer ends of the horizontal bars of each set is attached a vertical bar, B.

Each succeeding set of horizontal bars, A, is the breadth of one of the vertical bars, shorter than the preceding set, so that when closed, all the bars of the frame may be in the same plane, and the entire thickness of the closed frame may be no greater than the thickness of a single bar.

Through the other ends of the horizontal bars A are formed holes, through which is passed a long iron rod, C, which also passes through hollow tubes D, placed between the different groups of the ends of the said horizontal bars A.

The lower end of the rod C enters the foot-piece E a sufficient distance to be firm and stable.

Upon the upper end of the rod C is cut a screw-thread, upon which is screwed an ornamental nut, or cap, F, to secure the different parts of the pivoting, or hinge-bar C D E in place.

Upon each of the bars A, or upon any desired number of said bars are placed single bars G, through one end of each of which is formed a hole, for the passage of the rod C, the other ends of said bars G being left free.

The bars G are kept in place upon the bars A by pins a', attached to the said bars A, and entering holes in the said bars G, as shown in fig. 1.

When required for use, the free ends of the bars G are raised sufficiently to free them from the pins a', allowing them to be swung freely into any desired position.

To the side of the central one of the longest set of horizontal bars A is pivoted a button, H, which buttons into a slot, or recess in the vertical bar B, to which the ends of the shortest set of horizontal bars A are attached, as shown in figs. 1 and 2, so as to securely fasten the clothes-frame, when closed.

Having thus described my invention,

I claim as new, and desire to secure by Letters Patent—

1. The combination of the horizontal bars A, when made in sets of different lengths, vertical bars B, the single bars G, and pivoting, or hinge-bar C D E F, with each other, substantially as herein shown and described, and for the purpose set forth.

2. Securing the clothes-frame, when closed, by means of a button, G, pivoted to the central one of the longest set of horizontal bars A, and buttoning into the vertical bar B, attached to the ends of the shortest set of horizontal bars A, substantially as herein shown and described.

WILLIAM A. DAGGETT.
